(57) **CLAIM**

The ornamental design for a pot brush, as shown and described.

DESCRIPTION

FIG. 1 is a top, front and left side perspective view of a pot brush showing my design.

FIG. 2 is a bottom, rear and right side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of an area labeled 9 in FIG. 1. FIG. 10 is a front, top and left side perspective view illustrating the appearance of the claimed design in conjunction with a sponge-type brush head; and,

FIG. 11 is a front, top and left side perspective view illustrating the appearance of the claimed design in conjunction with a bristled brush head.

The short and uniformly-incremented broken lines illustrate features of the article of manufacture. The long-short broken lines illustrate the boundaries of the portion of FIG. 1 that is later shown in FIG. 9, as well as the bounds of the enlarged detail view that is FIG. 9. None of the elements shown in broken lines form part of the claimed design.
